C. MEE.
AUTOMOBILE MIRROR.
APPLICATION FILED DEC. 8, 1920.

Patented Apr. 26, 1921.

By *Frank Keiper*

Attorney

UNITED STATES PATENT OFFICE.

CHARLES MEE, OF ROCHESTER, NEW YORK, ASSIGNOR OF THREE-TENTHS TO FRANK KEIPER, OF ROCHESTER, NEW YORK.

AUTOMOBILE-MIRROR.

1,376,377.

Specification of Letters Patent. Patented Apr. 26, 1921.

Application filed December 8, 1920. Serial No. 429,263.

To all whom it may concern:

Be it known that I, CHARLES MEE, a citizen of the United States, residing at Rochester, in the county of Monroe and 5 State of New York, have invented certain new and useful Improvements in Automobile-Mirrors, of which the following is a specification.

The object of this invention is to provide 10 a new and improved form of mirror for an automobile, either open or closed car, by which the operator is enabled to see both the road ahead of him and the traffic back of him without turning his head.

15 This and other objects of this invention will be fully illustrated in the drawings, described in the specification and pointed out in the claims at the end thereof.

In the drawings, 20 Figure 1 is a perspective view of a section of the front of an inclosed car above the windshield, showing the mirror in place thereon.

Fig. 2 is a perspective view of the hinge 25 joint at the middle of the mirror.

Fig. 3 is a perspective view of the adjustable support for the hinge joint.

Fig. 4 is a top plan view of the end of 30 the mirror with the auxiliary mirror pivoted thereon.

Fig. 5 is a sectional view of the adjusting device on Fig. 3.

Fig. 6 is a detail view of the base plate ready to receive the stud.

35 In the drawings, like reference numerals indicate like parts.

In the drawings, reference numeral 1 indicates the support for the mirror, for which purpose in inclosed cars the front 40 of the car at the top above the windshield is ordinarily used, such cars ordinarily having a board or a plate extending across the front of the car between the uprights, which can be used to support the mirror.

45 On this plate is fastened the end brackets 2 and 3 and the intermediate bracket 4. Each of the end brackets consists of a single piece of angle iron, which is fastened to the base by screws. The forwardly projecting part of the angle iron is perforated to 50 form a bearing support for the end of the mirror.

The intermediate support comprises the

base plates 5 and 6, which are fastened to the body top of the car, by means of the 55 screw bolt and nut 7. To the bottom of the base 6 is fastened a hinge 8, having a horizontal axis, which in turn carries a link 9, having an upset end which is perforated and threaded to form a nut 10, which receives 60 the stud or operating screw 11. The operating screw has a winged head 12 keyed thereon by which the screw is turned. The screw is turned down near the end as indicated at 13 to form a small head 14 on the end. The 65 base plate 6 is cut with a slot 15 which runs lengthwise of the base, and at about the middle of the slot, this slot is pressed out to widen it to permit the introduction of the head 14 of the stud so that the reduced end of the stud is engaged with the slot. Thereafter, the plate is pressed back to narrow the slot, thus locking the stud in engagement with the slot. This permits the stud 11 to move along the slot while being 70 held in engagement with the base 6. With the parts assembled as shown in Fig. 5, the head 12 can be turned in the ordinary way. This will cause the link 9 to swing in and out on the hinge 8, thereby the head 14 of 75 the stud travels up in the slot as the link 9 moves out at the top and the head 14 moves down in the slot as the link 9 moves in at the top.

The mirrors 16 and 17 are provided, each 80 inclosed in a metal frame 18 and 19. These metal frames are joined together by the hinge 20, which hinge on one side is joined at the middle to the link 9. The outer ends of the frames 18 and 19 are provided with 85 the screws 21 and 22. The head of each of these screws is inside of the frame. The threaded stem of the screw extends out from the frame and through the opening provided therefor in the angle iron brackets 90 forming a pivot for the mirrors. The screws are held in place thereon by the wing nuts 23 and 24, which nuts are screwed up tightly on the threaded stems, securely 95 clamping the angle irons and mirror frames together. These thumb nuts are not used for the operation of the mirror, the tilting of the mirror being secured entirely by the screwing of the stud 11.

On the right hand side of the mirror 17 100 is shown the auxiliary mirror 25, hinged

thereon. This mirror 25 is hinged to the top and bottom of the frame 19 by the hinges 26 and is held in the desired angular position by the link 27, which is slotted at the end to receive the screw 28, on which it is clamped by the wing nut 29. A washer 30 is interposed between the link 27 and the frame of the mirror 25. By loosening the thumb nut 29, the mirror 25 can be set at any angle desired and clamped in place. The driver of the car usually sits on the left hand side, and this mirror is, therefore, preferably located on the right hand side so that the driver can see everything on the left hand side of the car.

The operation of the mirrors 16 and 17 is as follows:

After the mirrors are in place in the car, they will normally stand vertically and in a straight line with each other although this is not essential. The driver turns the thumb screw 12, which causes the mirrors 16 and 17 to move out or in at the top, thus causing the two mirrors, as they move out, to stand at an angle to each other. As they move out, they tilt on the pivots 21 and 22. Ordinarily the mirrors are placed well above the eye of the driver and by moving the screw 11, the mirrors are tilted so as to reflect into the driver's eye the road and the traffic thereon behind him. Because the mirror bends at the middle, the driver is enabled to see both sides of the street so that a wide range of vision is given. The mirrors can be pitched to accommodate a tall driver or a short one in an instant so that he can always see the particular zone of the road that he wants at any distance behind the car and it can also be pitched far enough so that he can even see the persons in the car behind him. It also enables those in the rear seat of the car to see the reflection of the road and traffic behind the car.

It will also be understood that the brackets 2 and 3 may be made of sheet metal that will spring to some extent, this being necessary as the mirrors swing forward at the middle, and the trunnion bearings, that engage with the brackets, are placed somewhat below the operating screw 11, by which the mirrors are moved in and out at the top. This tends to hold the mirrors firmly against rocking in any position to which they are moved.

It will also be understood that the mirror, instead of being made in two pieces, hinged at the middle, may be made in one single piece that extends clear across the car and will be supported on the ends by the trunnion bearings shown. In this case, the compound hinge at the middle may be omitted, but the screw for adjusting will be retained. The mirror will be supported at the ends and held against vibration in the middle. If desired, a hinge may be used to support the mirror in the middle, but the center of rota-

tion of the hinge must be in line with the center of the trunnion bearings at the end.

I claim:

1. A mirror having two sections hinged together end to end, trunnion bearings for the outer ends of said sections, said sections normally standing in line with each other, means for moving said hinged joint out to make said mirrors stand at an angle to each other. 75

2. A mirror having two sections hinged together end to end, trunnion bearings for the outer ends of said sections, means for rocking said mirrors on said trunnion bearings.

3. A mirror having two sections hinged together end to end, trunnion bearings for the outer ends of said sections, means for moving said hinged joint out at the top to move said mirrors angularly to each other and rock them on said trunnion bearings. 80 85

4. A mirror, having an adjustment comprising a base plate, a link pivoted thereto, a threaded nut in the free end of said link, a threaded screw mounted to turn in said nut, said base plate having a slot therein, said screw having a reduced portion engaging with said slot, said screw, when turning, causing said link to swing in or out, the end of the screw moving along the slot. 90

5. A mirror having an adjustment, comprising a base plate, a link hinged thereto, said mirror having two sections, joined by a hinge, one side of said hinge being fastened to said link and swinging with it, the outer ends of said sections being supported on 100 bearings. 95

6. A mirror having two sections, connected by a hinge joint, trunnion bearings on the outer ends of said sections, means for swinging said mirror sections on said trunnion bearings and said hinge joint, and holding them in position. 105

7. A mirror having a surrounding frame, an auxiliary mirror having a surrounding frame hinged at the top and bottom to the first named frame, a slotted link hinged to the first named frame, a thumb screw and nut on the second frame engaging said link to fasten said auxiliary mirror in a variety of positions. 110

8. In a mirror, the combination of a base plate, a plate pivotally mounted thereon, a screw connecting said plates at one side of said pivot to rock and hold said second plate, a mirror section fastened to said plate and 120 rocking therewith, and a pivoted support for said mirror at the end.

9. In a mirror, the combination of a base plate, a plate pivotally mounted thereon, mirror sections attached to said plate and 125 extending both ways therefrom, pivotal supports at the outer ends of said mirror sections permitting the rocking of said mirrors with the plate.

10. In a mirror, the combination of a 130

base plate, a plate pivotally mounted thereon, mirror sections attached to said plate and extending both ways therefrom, pivotal supports at the outer ends of said mirror sections permitting the rocking of said mirrors with the plate, said mirror sections being cut away at the corner at one end of the plate to expose the plate, a screw for rocking said plate and mirror sections, said screw 10 projecting from the exposed part of the plate between the mirror sections.

11. A mirror having two sections fastened together end to end, trunnion bearings for the outer ends of said sections, a bearing supporting the inner ends of said mirror sections and permitting the sections to rock thereon.

12. A mirror having two sections joined together end to end, said mirror sections having trunnions at the end on which to rock, a screw located between the mirror sections to rock them on their trunnions and hold them in adjusted position.

13. A mirror having two sections joined together end to end, said mirror sections having trunnions at the end on which to rock, a screw located between the mirror sections to rock them on their trunnions and hold them in adjusted position, a bearing 25 supporting said mirror sections at the middle and on which they are adapted to rock.

14. A mirror having two sections joined together end to end, said mirror sections having pivotal supports at the ends on which 30 to rock and means located between the end supports to simultaneously rock said mirrors.

15. A mirror having two sections joined together end to end, said mirror sections 35 having pivotal supports at the ends on which to rock and means located between the end

supports to simultaneously rock said mirror sections, said means holding them in any predetermined position.

16. A mirror having two sections hinged together end to end, trunnion bearings for the outer ends of said sections, brackets on which said bearings are supported to turn and on which they are fastened against end-wise movement, means for moving the 45 hinged joint of the mirrors outwardly and drawing the outer ends of the mirror sections toward each other and springing the brackets toward each other.

17. In a mirror, a hinge having a swinging plate and a fixed plate, a screw connected by its threads to the swinging plate, said screw having a head engaged below the stationary plate by which it is held against longitudinal movement, a mirror attached 50 to the swinging plate and swinging therewith.

18. In a mirror, a hinge having a swinging plate and a fixed plate, a screw connected by its threads to the swinging plate, said 55 screw having a head engaged below the stationary plate by which it is held against longitudinal movement, a mirror attached to the swinging plate and swinging therewith, a second plate fixed below said fixed plate 60 against which the head of the screw rests.

19. A mirror having trunnions on the ends thereof on which it can rock, a screw extending transversely to the mirror and out of line with the trunnions and having a positive engagement with the mirror, means to hold said screw against longitudinal movement and permitting it to turn, whereby on 75 the turning of the screw the mirror is swung on its bearings.

In testimony whereof I affix my signature.
CHARLES MEE.
